UNITED STATES PATENT OFFICE

152,231

DESIGN FOR A COMBINATION ASH TRAY AND CIGARETTE SNUFFER

George B. Weldon, East Orange, N. J.

Application October 8, 1947, Serial No. 141,802

Term of patent 7 years

(Cl. D85—2)

To all whom it may concern:

Be it known that I, George B. Weldon, a citizen of the United States, residing at East Orange, in the county of Essex and State of New Jersey, have invented a new, original, and ornamental Design for a Combination Ash Tray and Cigarette Snuffer, of which the following is a specification, reference being had to the accompanying drawings, forming a part thereof.

In the drawings:

Fig. 1 is a perspective view of a combination ash tray and cigarette snuffer, showing my new design.

Fig. 2 is a top plan view thereof.

I claim:

The ornamental design for a combination ash tray and cigarette snuffer, as shown.

GEORGE B. WELDON.
